UNITED STATES PATENT OFFICE.

OVERTON WINSTON, OF MINNEAPOLIS, MINNESOTA.

HEADLIGHT.

1,319,822.

Specification of Letters Patent. Patented Oct. 28, 1919.

Application filed February 19, 1917. Serial No. 149,392.

To whom it may concern:

Be it known that I, OVERTON WINSTON, a citizen of the United States, residing at Minneapolis, in the county of Hennepin and State of Minnesota, have invented certain new and useful Improvements in Headlights; and I do hereby declare the following to be a full, clear, and exact description of the invention, such as will enable others skilled in the art to which it appertains to make and use the same.

My present invention relates to headlights and is particularly directed to an improved form of lens and to an improved relative arrangement thereof, in respect to a concave reflector and an electric light bulb within the latter. Generally stated, the invention consists of the novel construction and combination of parts hereinafter described and defined in the claims.

In the accompanying drawings which illustrate the invention, like characters indicate like parts throughout the several views.

Referring to the drawings:

Figure 1 is a vertical axial section showing a headlight embodying my invention and wherein a two-filament light bulb is employed as a means for shifting the light source from the axis of the reflector to a point vertically above said axis;

Fig. 2 is an elevation looking at the inner face of the lens;

Fig. 3 is an enlarged fragmentary section taken approximately on the line 3—3 of Fig. 2;

Fig. 4 is a fragmentary view, in inner face elevation, showing a segmental portion of the lens;

Fig. 5 is a longitudinal section taken approximately on the line 5—5 of Figs. 2 and 4;

Figs. 6, 7, 8, 9, 10 and 11 are fragmentary sections taken, respectively, on the lines 6—6, 7—7, 8—8, 9—9, 10—10 and 11—11 of Fig. 4;

Fig. 11^a is an enlargement of one of the prismatic sections taken, for example, in Fig. 11;

Fig. 12 is a view corresponding to Fig. 1, but showing a headlight having a single filament light bulb.

Of the parts of the headlight, the numeral 13 indicates the casing, the numeral 14 the clamping ring thereof, the numeral 15 the concave reflector, the numeral 16 the electric light bulb, and the numeral 17 the

lens. The reflector 15 is preferably a hyperbolic reflector and it is provided with an axial passage through which the shank of the bulb 16 projects and is held by a suitable support. This bulb support, so far as this invention is concerned, may be of any suitable construction, but as shown, comprises a shank engaging sleeve 18 and a tubular socket body 19 screwed into a flanged hub 20 secured on the back of the reflector.

The bulb shown in Fig. 1 is a two-filament bulb, the one filament having its hot spot at *a* and the other having its hot spot at *b*. The point *a* is at the axis of the reflector and preferably also at the focal center thereof. The point *b* is vertically above the axis of the reflector. By means of a three-lead circuit 21, 22 and 23, which includes a battery 24 and switches 25 and 26, either of the two filaments *a* or *b* may, at will, be energized and used as the light source of the headlight. These electrical connections are more fully disclosed in my pending application S. N. 86,852, filed of date March 27, 1916, and entitled "Headlights."

In Fig. 12, the light bulb 16 is provided with a single filament *c*, the hot spot of which is at the axis of the reflector and preferably also at the focal center thereof. This filament is connected to a battery or source of electrical energy 27 by leads 28, in any one of which is a switch 29.

We will now consider the novel construction of the lens, the preferred form of which is illustrated in the drawings, and which, described in detail, is as follows:

Considerably more than the upper half of this lens 17 is formed with radial prismatic segments, while considerably less than the lower half of said lens is preferably made in smooth parallel surfaces. The segmental prisms radiate from the center of the lens or from the axis of the reflector and diminish in depth or thickness from the rim or outer portion thereof toward the said center. Preferably, the outer face of the lens is smooth and flat and the projecting beveled portions of the prisms are on the inner face thereof.

In the drawings, the said beveled surfaces of the prismatic segments are indicated at 17^a. The beveled surfaces that are on opposite sides of a vertical plane intersecting the axis of the reflector, incline or bevel in reverse directions, and in such direction that they increase the thickness of the prisms in

both directions circumferentially away from the upper vertical line or point. This direction of bevel is important because it causes the rays that leave the front face of the lens to be given a material downward deflection, or in other words, projection below the radial planes of both reflected and direct rays. The effect of this is to produce a general downward deflection of the light beam, so that a very much greater part thereof will reach the ground than with any lens known to me. Moreover, it is the rays of the beam that ordinarily are projected upward and which produce blinding effects, but do not light the road, that are thus deflected or refracted and turned downward onto the road. This arrangement also permits the lower portion of the lens to be made smooth, so that the rays which, with a hyperbolic reflector, are primarily, or by the reflector itself, directed downward at a diverging angle to the axis of the reflector, will be unobstructed, and hence, have their full road lighting effect. This is especially important with pressed lenses in which irregularities of any kind have a much greater light obstructing effect than in a cut glass lens.

To still further improve the lighting effect, that is, the distribution of the light beam onto the road, the various prismatic surfaces 17^a, in a circumferential direction from the upper vertical line, are progressively given increased angle. For example, the first or uppermost prismatic surface 17^a might have one degree of divergence from the plane of the lens, the next two degrees, the next three degrees, and so on, until the horizontal plane is reached and which, as illustrated, such horizontal radiating prismatic surfaces would be a downward divergence or say twenty three degrees.

Below the horizontal plane, the said prismatic surfaces 17^a are progressively decreased in the angle of their level and also in circumferential extent, as shown in Fig. 2. This progressively decreases the downward deflection given to the light rays from points below the horizontal plane. In Fig. 2, the small numerals marked adjacent to the right hand prismatic segments indicate the angles thereof, in respect to the plane of the lens.

The manner in which the segmental prisms are distributed and the order in which their bevel is varied, is capable of a wide range of modification, but highly satisfactory results are obtained by substantially the construction illustrated in the drawings and above described in detail.

With the two filament light bulb, or shifting light source shown in Fig. 1, there will be the above noted downward deflection of the beam when the light source is at the point *a*, but this downward deflection will be materially increased when the light source

is shifted from *a* to *b*. Hence, the shifting light source, in combination with a lens, such as described, makes possible a light beam of long projection, but with a maximum amount of light on the road and minimum amount of light above the road, such as required for country road driving, when the light source is at *a*. An ideal beam for headlights for city street driving is, as already indicated, produced when the light source is at the vertically offset point *b*.

In the use of a headlight with an ordinary reflector adjusted so as to throw approximately the lower half of the light beam upon the ground, which is a quite common arrangement, the lower half of the light beam will be distributed over many hundreds of square feet of road surface, and per unit of surface, the road will be given but a very small percentage of light, as compared with the amount of light thrown upon a vertical object in the road, by the upper half of the light beam. This is a result just reverse from that desired. An ideal arrangement would be one in which there would be at least as much light, per unit of surface, thrown upon the road as there would be upon a vertical object above the road, and such an arrangement, obviously, requires very much the greater part of the light beam to be distributed on the ground and a very minor part of the light beam to be diffused above the road. This ideal result is closely approximated by the use of the improved lens above described, which, as already stated, produces very great downward deflection of the more intense rays of the light beam and diffuses some, or a minor part, of the less intense light rays, above the road.

The lens herein disclosed involves highly important features which, both generically and specifically considered, are novel and from which greatly improved road lighting effects may be produced.

Obviously, the diverging arrangement of the prisms or prismatic portions with adjacent faces beveled in the same general direction produces a drift of the beam and a highly desirable road illumination. To illustrate, the prismatic portions or segments that are close to the top of the lens produce a very considerable lateral drift or deflection of the light rays, and to a less extent, a downward drift or refraction of the light rays; while the diverging sections or portions that are nearer to the horizontal diameter of the lens produce a very considerable downward drift or refraction of the light rays and to a much less extent, a lateral refraction or spreading of the light rays. In the upper portion of the light beam, the variation of the drift from lateral toward downward deflection is progressive and the beams is thus diffused laterally and deflect-

ed generally downward with two important results, to wit, the greater part of the beam is thrown onto the road where it is required for good lighting and a minor portion thereof is spread out and diffused, so that the beam will not have a blinding effect, because there will be a gradual change from mild to more intense light areas.

The two groups of prisms found, the one in the upper right hand and the other in the upper left hand quadrant of the lens, produce a drift of the beam in opposite general directions circumferentially of the lens; and the progressive bevel of the adjacent refracting surfaces of the prisms gives a progressively increasing depressing refractory action of the rays of the light beam.

What I claim is:

1. In a headlight, the combination with a reflector and a light source therein, of a lens having adjacent diverging prisms forming a serrated surface with adjacent beveled faces inclining in the same general direction and having their angles to the basal surface of the lens progressively increasing in a direction circumferentially from the vertical diameter toward the horizontal diameter of said lens, said prisms being positioned in respect to said reflector and light source, to intercept upwardly projected rays from said reflector and to refract and depress the same.
2. A headlight comprising a reflector, a light source and a lens, said lens having adjacent diverging prisms forming a serrated surface with adjacent beveled faces inclining in the same general direction and which prisms, in a direction circumferentially from the vertical diameter toward the horizontal

diameter of said lens, have a progressively increasing depressing refractory action, said prisms being positioned in respect to said reflector and light source, so as to refract reflected rays that are ultimately in the upper portion of the projected beam.

3. A lens for headlights having radial prismatic segments, of progressively increasing inclination to the plane of the lens in opposite directions from the upper vertical segment thereof, the bevel of the said segmental prisms diverging in a direction circumferentially away from the upper vertical segment.

4. A lens for headlights having radial prismatic segments, of progressively increasing inclination to the plane of the lens in opposite directions from the upper vertical segment thereof, the bevel of the said segmental prisms diverging in a direction circumferentially away from the upper vertical segment, and the said lens below the horizontal having radial segmental prisms, the segments of which, progressively decrease in a downward direction.

5. A lens for headlights having radial prismatic segments that progressively increase in their angle to the plane of the lens throughout a portion of said lens and progressively decrease their angle to the plane of the lens in other portions of the lens.

In testimony whereof I affix my signature in presence of two witnesses.

OVERTON WINSTON.
